SINGLE STRING MUSICAL INSTRUMENT

John A. Kalosy, Caldwell, N. J.

Application January 4, 1950, Serial No. 136,765

4 Claims. (Cl. 84—296)

1

This invention relates to a novel single string musical instrument, the string of which is adapted to be vibrated by movement of a bow of the violin playing type thereover.

The invention has for an object to provide a novel construction of single string musical instrument having manipulatable means for varying the tension of the string whereby to produce the various tones or notes of a musical scale, means cooperative with the string being provided whereby to amplify the produced tones and thus to obtain mellow and pleasing musical quality of good volume and carrying power.

An illustrative embodiment of the invention is shown in the accompanying drawings, in which:

Fig. 1 is a top plan view of a single string musical instrument made according to the invention; Fig. 2 is a longitudinal sectional view of the same, taken on line 2—2 in Fig. 1; Fig. 3 is a horizontal sectional view thereof, taken on line 3—3 in Fig. 2; and Fig. 4 is a detail view of the coupling attachment whereby the string is operatively connected with the sound amplifying means of the instrument.

Similar characters of reference are employed in the herein-above described views, to indicate corresponding parts.

Referring to the drawings, the novel musical instrument of this invention comprises a hollow body 10 of suitable shape and design appearance which is formed by side walls 11, a bottom wall 12 and a top wall 13. The top wall 13 extends beyond one end of the body so as to provide a neck portion having a central bow passage opening 14 terminating at its outer end in an endwise open space 15, thus dividing the neck portion into two arms 16 and 17. Affixed to the body, to extend centrally through the interior thereof intermediate its top and bottom walls 12 and 13, are a pair of longitudinally disposed, laterally spaced frame bars 18, the outer end portions 19 of which are shaped to conform to margins of the opening 14 and end space 15 of said neck portion. Said end portions 19 of the frame bars terminate in bearing portions 20 which border the sides of said end space 15. The outer end portions 19 of the frame bars are of increased height so that they abut and support the arms 16 and 17 of the neck portion in underlying relation thereto.

Supported by the frame bars 18, to extend across the undersides thereof within the interior of the body 10, is a bridge member 21. Mounted on the top of said bridge member 21, so as to be centrally located between said frame bars 18,

2

is a string anchor block 22 having a superposed clamp plate 23 adapted to be affixed thereto by suitable fastening means, such e. g. as fastening screws 24.

5 Mounted in the space 15 at the outer end of the instrument neck portion is a string tension control drum 25, the shaft 26 of which is journaled in the bearing portions 20 with which the outer ends of the frame bars 18 are provided. 10 One end of the shaft 26 is provided with a rearwardly extending crank-like lever arm 27 having a finger piece formation 28 which projects laterally beyond the adjacent outer side margin of the instrument neck portion, so as to be readily 15 accessible by the tone controlling hand of the operator while in playing position for manipulation.

The instrument string 29 is anchored by its 20 inner end to the anchor block 22 by means of the clamp plate 23. From said anchor block 22, the instrument string 29 extends longitudinally outward from the interior of the instrument body 10, thence across the opening 14 of the instrument neck portion to the tension control drum 25. The outer end portion of said string 29 is wound around said drum, preferably so as to form a plurality of convolutions 30 which encircle the latter, whereupon the terminal convolution is secured to the drum by suitable fastener means, such e. g. as a fastening screw 31. 25 The string 29 is thus stretched between the anchor block 22 and the drum 25 at a minimum tension, the drum being stopped against clockwise rotation and consequent relaxation of the string from such minimum tension by the 30 stopped engagement of the free end portion of the drum shaft lever arm 27 with the underside of the instrument neck portion (see Fig. 2).

Dependent from the bridge member 21 are 35 spaced bearing lugs 32 which extend in vertical planes parallel to the plane of the string 29. Mounted through the bearing lugs 32 are fulcrum pivots 33 by which an oscillator lever 34 is pivotally supported in downwardly spaced aligned relation to the string 29, and in the vertical plane of the latter. This oscillator lever 34 comprises an outwardly directed short arm 35, which underlies the string 29, and an oppositely extending and inwardly directed long arm 36. The lengths of said arms 35 and 36 are suitably relatively proportioned, preferably at a one to two ratio, whereby the length of the long arm 36 is twice that of short arm 35. Pivotally connected with the end of the short arm 35 is a transmission rod 37 which extends upwardly to the string 29, with its upper end portion fixedly

coupled to the latter. To provide such coupling, the upper end portion of said transmission rod 37 is bifurcated by a split 38 (see Fig. 4), the string 29 being entered in said bifurcated end portion of said transmission rod, and then said portion of the latter being squeezed into strong gripping or clamping engagement with the string. Said transmission rod is thus coupled to the string 29 at a point on the latter which is outwardly spaced from its anchored end. This point of attachment is predetermined so as to establish suitably relatively proportioned inner and outer lengths of the string, preferably at the ratio of one to seven.

The top wall 13 of the instrument body 10 is provided with a circular opening 39 of desired diameter, and suitably affixed to said top wall 13 and across said opening is a diaphragm 40. Preferably, said diaphragm comprises thin metallic sheet material, although it will be obvious that it may comprise any other suitable material. It has been found that a diaphragm of silver-aluminum alloy gives very satisfactory performance.

Pivottally connected with the end of the long arm 36 of the oscillator lever 34 is a second transmission rod 41, which extends upwardly to and for suitably fixed attachment to the center of said diaphragm 40.

Preferably, the bottom wall 12 of the instrument body 10 is likewise provided with a circular opening 42 across which extends a diaphragm 43 similar to said diaphragm 40. The provision of this diaphragm 43 not only contributes to the sound amplification of the instrument, but also aids in production of mellow and pleasing tone quality when the instrument is played. It will be understood, however, that provision of this second diaphragm 43, although preferred, is not essential, and it may be omitted from the instrument structure if desired.

In the playing of the instrument, the body 10 may be horizontally held between the player's hip and left arm, with the left hand underlying and supporting the neck of the instrument, but so that the thumb thereof may be applied to the finger piece formation 28 of the lever arm 27 by which the string tension control drum 25 can be actuated.

When the instrument is so held, or otherwise held suitable to the convenience of the player, the player applies a rosined hair bow of the violin bow type (not shown) to the string 29, by passing said bow perpendicularly through the opening 14 of the neck portion of the instrument, and then reciprocates the bow in contact with the string 29. The movement of the thus manipulated bow relative to the string 29 causes the latter to vibrate in vertical plane with musical note or tone producing effect. The string vibrations thus produced are transmitted by the string through the transmission rod 37 to the short arm 35 of the oscillator lever 34, thus causing oscillations of the lever in correspondence to the string vibrations. Such oscillation of the lever 34 effects like oscillatory movements of the long arm 36 thereof but of greater amplitude, and these movements are transmitted through the transmission rod 41 to the diaphragm 43, whereby the latter is vibrated correspondingly to the string 29, so that the produced note or tone is substantially amplified in volume and carrying power.

In the playing of the instrument in the manner above described, the player may vary the tone or note production of the string 29 at will by

manipulating the lever 27. By depressing said lever 27, the string tension control drum 25 is rotated counterclockwise. Rotation of the drum in such direction increases the tension of the string 29, and therefore increases the pitch of the produced tones. It will thus be understood that by manipulation of the lever 27, the drum 25 may be caused to rotate back and forth with string tension varying effect, and thus a succession of various musical notes or tones throughout the scale of a complete melody can be produced with novel and pleasing musical effect.

Having thus described my invention, I claim:

1. A single string musical instrument adapted to produce the notes and tones throughout the scale range of a complete melody comprising a body having a neck portion, a transverse shaft journaled in said neck portion, a string tension control drum of substantial diameter affixed on said shaft, a string having one end anchored to the body and its opposite end to the drum, and manipulating means for oscillating the drum to control tone production comprising a crank-like lever arm provided on said shaft and having a finger piece projecting laterally beyond the body neck portion for engagement by the tone controlling hand of the player, said lever arm being held in stopped engagement with the underside of the body neck portion by the tension of the string when said tension is at its low-pitch limit but subject to oscillatory movement above said limit whereby to rotate the drum for string tension and musical tone variation.

2. A single string musical instrument adapted to produce the notes and tones throughout the scale range of a complete melody comprising a hollow body having a neck portion, said body neck portion being provided with a bow passage opening perpendicular to the plane thereof, a transverse shaft journaled in said body neck portion, a string tension control drum of substantial diameter affixed on said shaft and disposed outwardly adjacent to the bow passage opening, a string having one end anchored within the hollow body and its opposite end wound around the said tension control drum and terminally affixed thereto, said string being arranged to extend across the bow passage opening, and manipulating means for the said control drum comprising a crank-like lever provided on said shaft, said lever being held in stopped engagement with the body neck portion by the tension of the string when said tension is at its low pitch limit but being subject to oscillatory movement away from such stopped position whereby to rotate the drum for string tension and musical tone variation, said lever having a finger piece formation projecting from its free end outwardly beyond the adjacent side of the body neck portion and accessible for manipulation by the tone controlling hand of the player.

3. A single string musical instrument as defined in claim 2, wherein the hollow body has an opening therein axially parallel to the bow passage opening in the neck portion thereof, the axis of said body opening being also located in the vertical plane of the string, a horizontally flat circular sound-amplifying diaphragm mounted in closing relation to said body opening, and means within the body for transmitting string vibration to the diaphragm and comprising a substantially straight lever mounted on an axis transverse to the string for oscillation substantially in the vertical plane of said string and having its inner end disposed beneath the center of said diaphragm, a vertical rod connecting said inner end

of said oscillating lever to the center of the diaphragm, and a second vertical rod connecting the outer end of said lever to the string.

4. A single string musical instrument as defined in claim 3, wherein the sound amplifying diaphragm is corrugated in concentric convolutions.

JOHN A. KALOSY.
